MACHINE FOR MAKING GARMENT PATTERNS

Joseph M. Shapiro, Ridgefield, Conn.

Application July 26, 1947, Serial No. 763,828

6 Claims. (Cl. 164—28)

1

The present invention is concerned with methods and equipment for the fabrication of garment pattern of thin paper.

It is among the objects of the invention to provide methods and machine installations for the above purpose by which the pattern, substantially regardless of the number and shape of its component blanks, is cut automatically and in rapid sequence from a continuous roll, wholly dispensing with the need for manually guiding a cutter about the outlines of the patterns and for stacking individual sheets preliminary to such cutting operation.

Among other objects is to provide a reliable method and a relatively simple and rugged machine installation for maintaining adequate control over the individual relatively flimsy pattern blanks after they are sheared from the sheet, and collecting the sets of blanks making up a pattern, and for folding the same rapidly and reliably to the desired size of package, all without manual intervention.

According to one feature of the invention the various blanks making up a pattern are cut from a continuous sheet of paper by a shearing action between two shearing and feed rollers that advance the paper stock sheet, desirably from a roll. The rollers comprise a die roller having shallow depressions therein distributed over the cylindrical surface thereof and corresponding in size and shape to the various blanks that make up the pattern and the coacting punch roller has correspondingly thin raised areas to mesh with the depressions in the die roller so that as the paper stock is fed between the two rollers, the pattern is blanked progressively in the rotation of the rollers and the severed blanks become lodged in the respective depressions of the die roller. Preferably the sheet is first passed between printing rollers that imprint the outline of the patterns and all other insignia upon the sheet preparatory to passing the same between the shearing rollers in registry with such printed areas.

Another feature is to collect the blanks that make up a complete pattern preparatory to folding the same. This may be accomplished by stripping the blanks from the depressions of the die roller, preferably pneumatically, and depositing upon a platform preparatory to folding the same, the set of diverse blanks that makes a complete pattern.

Another feature is a sequence of automatic folding operations, desirably by means of an installation comprising a platform centrally split

5 with an associated blade thereabove that descends and thereby folds the set of blanks along a fold line, feed means advancing the folded sheet to the next similar folding platform whose fold is in the same direction or at right angles to the direction of the first fold, the folding operations being of number and direction adapted to the size of package desired.

10 In the accompanying drawings in which are shown one or more of various possible embodiments of the several features of the invention:

Fig. 1 is a diagrammatic, perspective view of the equipment,

15 Fig. 2 is a fragmentary transverse sectional view on a larger scale through the contact region of the shearing rollers,

Fig. 3 is a diagrammatic end elevation of a part of the folding installation,

20 Figs. 4, 5, 6, 7 and 8 illustrate the successive stages in the folding of a typical set of blanks that constitutes a pattern,

Fig. 9 is a plan view showing one stage of the packaging operation, and

25 Figs. 10 and 11 are developed plan views of the cylindrical surface respectively, of the die roller and the punch roller.

Referring now to the drawings and particularly to Fig. 1 thereof, the paper P is fed in a continuous strip from a roll (not shown) between printing roller 12 and pressure roller 13, the former having distributed about the cylindrical surface thereof the printing conformation 14 which includes the outlines of the various blanks making up a pattern and any printed directions or other insignia commonly used on such patterns. The printing roller is inked in conventional manner from an inking roller 15 and may imprint the sheet directly, as shown, or by way of an offset roller (not shown) in manner which is evident to those skilled in the art.

30 The sheet with the recurrent pattern 14' that is thus imprinted thereon in the continuous rotation of rollers 12 and 13 is passed between a pair of shearing rollers. These rollers include a die roller 16 which is desirably, though not necessarily, the lower of the rollers and a coacting punch roller 17. The die roller has formed in the cylindrical surface thereof, and arranged to border the printed outlines 14' made by the printing roller 12, shallow depressions 18 corresponding in outline as to size and shape to the diverse blanks that make up the complete pattern. The punch roller 17 has thin raised areas 19 which correspond precisely in size, shape, outline and arrangement with the depressions 18 of the die

roller so that in the operation of the machine the two coating rollers will press the intervening sheet across the width thereof and act to feed the same forward. At the same time the raised portions 19 of the punch roller will enter and mesh accurately with the depressions 18 of the die roller and thereby progressively effect the shearing of the sheet and the lodging of the severed blanks within the respective depressions of the die roller. Figs. 10 and 11 show the developed surface of the die roller and the punch roller, respectively, illustratively showing a blouse pattern with the various blanks for a complete pattern distributed over the cylindrical surfaces of the respective rollers.

While the rollers may be made in other ways, it is preferred to form the depressions on the die roller from a single thin rectangular die sheet 20 of metal, desirably in the order of .002 inch in thickness, from which the respective pattern areas 18 have been blanked out. The die sheet thus blanked out is, after suitable hardening, welded upon a jacket sheet 20' of appropriate metal, and said jacket sheet 20' is enveloped about the core 16 of the die roller and removably clamped to the latter by means conventional in the printing arts and therefore not shown. Thus the shearing walls of the depressions 18 are along the cut thickness of the die sheet 20 and the jacket sheet 20' upon the die roller forms the floor of each depression 18. Similarly the blanks 19 of sheet metal, previously cut from the die sheet 20 (or blanks identical therewith) and suitably hardened, are properly distributed and welded to a jacket sheet 19' of appropriate metal and said jacket sheet is removably affixed to the core 17 of the punch roller in the same manner as is the jacket sheet 20' upon the die roller, so that the blanks 19 upon the punch roller are positioned for proper registry with the depressions formed in the die roller.

The unitary mutilated sheet P' which remains after the blanks have been cut therefrom, is desirably withdrawn by passing between a conveyor 41 thereunder and a series of horizontal rollers 41' desirably felt covered and extending parallel to the shearing rollers, thus frictionally feeding the flimsy blanked out remnant P' of the continuous sheet to feed the same to a collecting roller (not shown), which may be appropriately driven.

Inasmuch as the blanks of paper making up the pattern are quite flimsy, they are apt, in the absence of means for stripping them off, to remain in the respective die depressions of the die roller. Pneumatic means is shown for such stripping purpose. Preferably this means comprises a pipe 21 longitudinally of the die roller 16 (of tube stock several inches thick), and near the inner wall thereof. Pipe 21 is substantially immovably fixed somewhat in advance of the region of tangency and therefore of shearing between the two rotating shearing rollers 16 and 17 and has outwardly directed apertures 21' distributed along the length thereof. The perforated pipe 21 is supplied with compressed air through a pipe 22 axially of the die roller 16 feeding through a radial elbow length 23 into the inlet end of said pipe 21. The entire cylindrical area of the die roller 16 is foraminated as at 24 with numerous small closely distributed radial bores which register with corresponding foraminations 24' in the emplaced jacket sheet 20'. The areas of the depressions 18 in the die sheet 20 expose said foraminations, the unperforated areas of said die

sheet covering those perforations 24 not within the confines of the respective die depressions.

In advance of the die roller 16 is a platform desirably in the form of an intermittent conveyor 25, upon which the set of blanks making up the pattern is deposited as a result of the pneumatic stripping and blowing action. The larger blanks will be advanced relatively little by reason of their greater weight under the pneumatic blowing action and the smaller blanks will be advanced somewhat further so that the various blanks making up the complete pattern cut out in each complete revolution of the shearing rollers will be deposited in a batch or set, as approximately suggested in Fig. 4, as they leave the shearing rollers. The intermittent conveyor, desirably in the form of a belt conveyor 25, is timed to advance only after a complete revolution of the shearing die rollers 16, 17, so as to shift the collected set of sheets making up a complete pattern to a folding platform 26 adjacent thereto, an intervening perforated air pipe 27 assuring the smooth delivery thereof upon the said folding platform without wrinkling. Said folding platform desirably has a median longitudinal opening 28 accommodating a pair of coating folding rollers 29 lengthwise of the platform, the bearing mounts 30 of which are desirably in the end portions of said platform. The rollers 29 may be constantly rotated inwardly so that they will, upon the timed descent of a folding blade 31 normally directly above the line of tangency of the rollers, fold and feed downward the set of blanks making up the pattern. Desirably the rollers 29 are connected with a downward feed which may be pairs of additional horizontal rollers 32 and 33 driven to propel the longitudinally folded set of patterns downward to a conveyor 34 which may be constantly operated to feed the previously folded set of sheets forward for another folding operation. Where the second fold is to be at right angles to the first fold, the conveyor 34 delivers to another horizontal conveyor belt 35 extending at right angles thereto, an intervening perforated air pipe 36 assuring the reliable delivery of the folded sheets thereto. The conveyor belt 35 in turn feeds to a second folding platform 37 aligned therewith, and across an intervening perforated air pipe 38. The rollers 39 of platform 37 extend at right angles to rollers 29 so that the action will of course be to fold the previously folded set of blanks making up the pattern along a line at right angles to the first fold. It will be understood that in like manner further folding platforms, each connected to the previous one by a feed such as 32, 33, 34, would be utilized to fold the set of blanks making up the pattern along lines and in direction such that the pattern is folded to the size of package, suitable for introduction into the particular envelope in which the pattern is to be enclosed.

The folds need not necessarily alternate at right angles to each other but there might be cases in which two or more consecutive folds are made, either longitudinally or transversely of the stacked patterns. When any fold is in direction at right angles to the previous one, there would be in addition to feed 32, 33 and conveyor 34, a further interposed conveyor belt such as 35 to change the direction of propulsion of the partly folded pattern. It will be understood that the sequence of folding platforms would be set up in accordance with the particular pattern to be cut and packaged.

Illustratively, Fig. 4 shows the set of blanks

making up a typical pattern, as deposited upon platform 26. Fig. 5 shows that blank folded once longitudinally along line *a*—*a* to the position it will assume after leaving the folding platform 26. Fig. 6 shows the longitudinally folded set of Fig. 5 as folded transversely along line *b*—*b* to the position it would assume after passing through folding platform 37. Similarly Fig. 7 shows the pattern in the next stage of folding that is along the line *c*—*c* of Fig. 6 and finally Fig. 8 shows the folding along the line *d*—*d* of Fig. 7, preparatory to introduction into envelope 40, shown in Fig. 9.

While the pattern shown is a relatively simple one for a blouse, it will be understood that the invention lends itself to the cutting and packaging of fairly elaborate patterns involving many diversely shaped blanks, it being understood of course that the cylindrical surface area of each shearing roller would have to be sufficient to accommodate the various blanks to be cut therefrom. Manifestly if the pattern is too elaborate to be accommodated on one set of shearing rollers of practicable diameter, it might be prepared from two or more sets of such rollers in distinct operations and the two or more sets of collected and folded patterns could then be introduced into a single package.

While the operation is apparent from the foregoing description, it may be briefly summarized as follows:

The continuous sheet *P* of paper from a roll progressively passes between rollers 12 and 13 for imprint of the pattern and other insignia thereon and then passes between the die roller 16 and the punch roller 17. In the shearing operation, as best suggested in Fig. 2, each raised portion 19 of the punch roller presses the paper into the corresponding depression 18 of the die roller at its forward edge, and by reason of the snug fit of the punch 19 into the corresponding die cavity 18, the paper is sheared near the forward edge thereof and as the rotation of the rollers proceeds, the paper is sheared in the general direction of rotation along the periphery of the respective blanks to be formed, each blank being completely cut out and forced into the corresponding depression 18 as the trailing end of the die depression leaves the associated end of the raised portion 19 of the punch roller 17. The compressed air through the axle 22, elbow 23, and pipe 21 blows through the otherwise open perforations 24 that are covered by the respective paper blanks in the die roller depressions 18. Accordingly, as the advance end of each die depression comes into registry with the pipe 21, the paper blank is stripped off and out, as suggested at *B* in Figs. 1 and 2. As each die depression passes completely beyond the perforated pipe 21 in the rotation of the die roller, the corresponding blank *B* is entrained by the expelled air and then is deposited upon the intermittent conveyor 25. Thus the various blanks formed in one revolution of the coacting shearing rollers 16 and 17 are deposited in a set, such as shown in Fig. 4. By reason of the fact that the smaller blanks such as *b* are lighter than the larger ones, they will be propelled further by the expelled air so that various blanks making up the pattern will substantially cross the median line *a*—*a* shown in Fig. 4. The mutilated unitary remnant sheet *P* initially drawn manually over the conveyor 41 and held by rollers 41' is withdrawn as the blanks are cut therefrom by winding the

same upon the appropriately driven collecting roller therefor (not shown).

As soon as the shearing rollers have made a complete turn and the complete set of blanks *B* has been deposited upon conveyor 25, the latter is caused to advance to deliver the set of blanks to the folding platform 26. Thereupon the blade 31 in its timed action is caused to descend for the first folding operation and the folded blanks are passed along by feed 32, 33 to conveyor belt 34 and thence to transverse conveyor belt 35 to the next folding platform 37 and for transverse fold, thence onward in the manner previously set forth to fold the pattern to the size of package desired.

As many changes could be made in the above method, machine and installation, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. In an installation for automatically producing garment patterns, the combination of a pair of coacting rollers including a die roller having shallow depressions distributed over the cylindrical area thereof corresponding in size and shape to the respective blanks that make a complete pattern, a coacting punch roller having thin raised portions distributed over its surface to correspond accurately in size and shape to and to mesh with the die depressions and thereby in operation progressively to shear blanks from a continuous sheet fed between the rollers and to press these blanks into the die depressions, said die roller being foraminated, and pneumatic pressure discharge means within the die roller directed substantially along and somewhat in advance of the line of engagement between said rollers, progressively to strip the severed blanks from said die roller as they are sheared from the strip.

2. In an installation for fabricating garment patterns, a pair of coacting shearing rollers comprising a die roller and a coacting punch roller, the die roller having a plurality of shallow depressions in its cylindrical surface of diverse size and shape corresponding to the various blanks making up a complete pattern, the punch roller having corresponding thin raised portions on its cylindrical surface meshing with the depressions of the die roller, a conveyor in advance of said rollers for withdrawing the unitary remnant of the sheet from which the recurring sets of blanks making up the recurring patterns are cut, pneumatic means for stripping the blanks lodged in the respective depressions of the die roller, and intermittent conveyor means adjacent the die roller upon which the set of blanks making up a pattern is collected preparatory to advance thereof by the conveyor.

3. The combination recited in claim 2 in which the stripping action is effected by means of a perforated tube within and adjacent the inner surface of the die roller in substantially fixed position somewhat in advance of the region of contact between the two shearing rollers, in which the cylindrical surface of the die roller is foraminated and in which compressed air is forced

through the pipe by way of an inlet coaxial with the die roller.

4. The combination set forth in claim 2 in which the die roller has a jacket sheet removably affixed thereon, and a thin hardened metal die sheet is rigidly affixed upon the outer face of the jacket sheet, said die sheet having apertures therethrough of size and shape corresponding to the various blanks making up a complete pattern, and the pressure roller has a jacket sheet removably affixed thereon, the various blanks cut from the jacket of the die roller being rigidly affixed upon the outer face of said jacket sheet.

5. The roller shearing device claimed in claim 4 in which the die roller and the corresponding jacket sheet are foraminated, the die sheet closing all foraminated areas except those exposed through its blank-shaped apertures.

6. The combination set forth in claim 2 in which said die roller is foraminated and said pneumatic pressure discharge means are within the die roller and directed substantially along and somewhat in advance of the line of engagement between said rollers whereby when air is blown through said discharge means, the severed

blanks will be progressively stripped from said die roller as they are sheared from the strip.

JOSEPH M. SHAPIRO.
